[54] COSTUME

[76] Inventor: David Johnson, 2800 Veterans Memorial Blvd., Suite 104, Metairie, La. 70002

[] Term: 14 Years

[21] Appl. No.: 388,444

[22] Filed: Jun. 14, 1982

[52] U.S. Cl. D2/79; D2/29;
D2/33

[58] Field of Search D2/79, 29, 33; D21/148

[56] References Cited

U.S. PATENT DOCUMENTS

D. 64,439 4/1924 Browne D2/79
D. 149,390 4/1948 Swedlin D21/148
D. 268,744 4/1983 Gibsone et al. ..... D2/79 X

OTHER PUBLICATIONS

Collegeville Costumes, Collegeville, Pa., '76 Catalog, p. 12.

Encyclopedia Americana, ©'78, vol. 23, p. 107, Raccoon.

Primary Examiner—Jane E. Corrigan
Attorney, Agent, or Firm—Pravel, Gammell, Hewitt & Kimball

[57]

CLAIM

The ornamental design for a costume, as shown and described.

DESCRIPTION

FIG. 1 is a side elevational view of a costume showing my new design, with the left sock obscured by the environmental broken line shoe and the shoe forming no part of the claimed design;

FIG. 2 is a front elevational view, with the broken line environmental shoes included; and

FIG. 3 is a rear elevational view.